ADJUSTABLE CURVE RULER

William S. Weston, Douglaston, N. Y.

Application May 12, 1934, Serial No. 725,285

2 Claims. (Cl. 33—177)

The invention relates to an adjustable ruler for the use of draftsmen and others when drawing or checking curves of either short or long radii, under conditions when the use of an ordinary drafting compass, or beam compass, is impracticable. It comprises a flexible arc member of constant length; rigid end frames or members attached to the ends of the arc member and provided with edges or other means for indicating or defining lines that are tangent and radial respectively to the arc member at the ends thereof; and a set of bars pivotally connecting the rigid end frames and arranged to hold the ends or tangent points of the flexible arc member at the correct distance apart and the tangent and radial line indicating means in correct relation to the arc member when the latter is flexed to any desired radius.

My present invention is a curve ruler utilizing the fundamental principle of construction and operation disclosed in my Patent No. 1,893,689, issued January 10, 1933; and is also a modification of the ruler for drawing arcs of circles disclosed in my Patent No. 1,953,282, issued April 3rd, 1934. The invention is hereinafter more fully described, illustrated in the accompanying drawings, and the novel features more particularly pointed out in the appended claims.

Referring to the drawings:

Fig. 1 is a plan view of the instrument with the arc member in the straight line position.

Fig. 2 is a plan view of the instrument with the arc member flexed to an arc of a circle through an angle of 90 degrees.

Fig. 3 is a cross section on the line 3—3 of Fig. 1.

Figs. 4 to 7, inclusive, are geometric illustrations used to describe the fundamental facts governing the construction and relation of the flexible arc member, the rigid end members, and the pivotal connections between the end members, as embodied in the complete instrument of Figs. 1 and 2.

The design of my adjustable curve ruler is based on the fact that, in a curve ruler having a flexible curve member of constant length with rigid end members fixed at the ends thereof, there are a series of points in fixed position relative to one end member, each of which may be paired with and held at constant distance from a different point in a series of points which are in a fixed position relative to the other end member, when the flexible member is adjusted to an arc of a circle. As a basis for the construction

of my improved instrument, I utilize two pair of these fundamental points.

Referring now to the geometric illustrations, Figs. 4 and 5, the line A represents the flexible member of the instrument with its ends indicated by the letters PC and PT; these letters being commonly used by engineers and draftsmen to mark the two ends of a curve. At each end the lines T and R represent edges carried by the rigid end members and held tangent and radial to the curve of the flexible member at the ends PC and PT. In the following description, the letters PC and PT are used to designate the end members. The two pair of fundamental points are indicated by the letters O₃ I₄ and O₄ I₃, the same as shown in Fig. 8 of Patent 1,893,689. For a flexible arc member 7.854 units long, the fixed location of the points relative to the adjacent PC or PT and tangent T is given in Fig. 4. The distance apart for the points of each pair is 4.5 units, remaining constant when the flexible member is curved to the arc of a circle like that shown in Fig. 5. In my present construction, instead of connecting these points direct, as illustrated by full lines in Figs. 4 and 5, I use a parallelogram of bars held in parallel relation to the line connecting the points of each pair of fundamental points. The two parallelograms are illustrated by full lines in Figs. 6 and 7. An important detail governing the construction of the parallelograms is the location of the pivot point D, constituting the intermediate connection between the two parallelograms. The point D is located half way between the fundamental points I₃ and I₄, on a straight line through those points for all positions of adjustment. A point C₁ used in determining the location of some of the pivot points is located half way between fundamental points O₃ and I₃ on a straight line through those points. Point C₂ is similarly located between points O₄ and I₄. A line from C₁ to D is parallel with and equal to half the length of the line connecting fundamental points O₃ and I₄ for all positions of adjustment. This is also true for the line C₂ D parallel with the line O₄ I₃. For an instrument in which the line connecting the points in each pair of fundamental points is 4.5 units long, as shown in Fig. 4, the length of the parallel lines C₁ D and C₂ D would be 2.25 units long.

The parallelograms are constructed in parallelogram relation to the lines C₁ D and C₂ D respectively with two sides necessarily equal in length to those lines.

Referring to the parallelogram at the PC end

of the instrument: Pivot points G_1 H_1 constituting the outer end are in fixed positions on the end member and are in line with the point C_1 . Pivot points E_1 J_1 constituting the inner end of the parallelogram are made on a bar which is extended to the point D where it is pivotally connected with a similar extension of the bar of the parallelogram at the PT end. The bars DE_1 and DE_2 are of equal length. The bars H_1 J_1 and G_1 E_1 are parallel with and equal in length to the theoretical line C_1 D . It may be noted that the bar H_1 J_1 could be moved up to and mounted on the line C_1 D . The objection to that location is that pivot H_1 located at C_1 would be in the way 15 of the flexible member for a short radius curve like that of Fig. 7. The parallelogram at the PT end is a duplicate in reverse of the PC end parallelogram, as indicated by the same letters with the sub-numeral 2.

An important novel detail in the construction of my improved instrument may now be described. To hold the intermediate pivot point D , connecting the two parallelograms, in line with the fundamental points, I_3 and I_4 I provide means for holding pivot points E_1 and E_2 of the two parallelograms in line with a fixed point on each end member, points F_1 and F_2 . The line through these points is a straight line parallel with the line through points I_3 I_4 and pivot point D . The point F_1 is so located on the PC member that the line between points I_3 and F_1 is equal in length and parallel with the bar DE_1 . On the PT member point F_2 is so located that line I_4 F_2 is also equal in length and parallel with the bar DE_2 . As a result of this construction the pivot point D is held in a straight line and at equal distances from the points I_3 and I_4 for all angular movements of the parallelograms in the adjustments of the flexible member of arcs of circles.

Referring now to Fig. 1, the means provided for holding points F_1 F_2 and pivot points E_1 E_2 in a straight line is a flat bar K with slots for the E_1 E_2 pivot points and for a bolt at point F_2 on the PT end member, permitting all four points to be moved toward each other in the process of adjusting the instrument from the straight position of Fig. 1 to that for an arc of a circle like that of Fig. 2. The end of the bar at the point F_1 on the PC end has a pivotal connection only. When the instrument is adjusted to the desired curvature, the adjustment is held by means of a clamp nut on the bolt at point F_2 . A plate L carried by the bolt is marked with an arrow point which indicates by means of a scale drawn on the bar K the radius of the curve to which the instrument is adjusted. For an arc member 7.854 units long curved through 90 degrees, the radius would be 5, as shown in Fig. 2. For a larger instrument the radius for any angle would be proportionally longer. The scale which would also be longer could be marked much finer than shown in Figs. 1 and 2. The bar K may be termed a base element utilized in the control of the pivotal relation between the end members.

It is to be noted that, with the bars DE_1 and DE_2 equal in length, their angles with the straight guide bar K continue to be equal when shifted from the position in Fig. 1 toward the position of Fig. 2. Because of that fact and the parallelogram relation of the end members to those bars, the angular relation of the end members with the bar K also remains equal.

In the construction of the instrument based on the fundamental points and dimensions shown in Fig. 4 the following procedure may be followed: Referring to the PC end in Fig. 6, the pivot points G_1 and H_1 are located on the frame in line with the point C_1 , the distance between these points being optional. The choice in the location of the points G_1 and H_1 also determines the length of the bar E_1 J_1 D and the relative location of its pivot points, because the bars H_1 J_1 and G_1 10 E_1 connecting the bar E_1 J_1 D with the frame are equal in length and parallel to the line C_1 D . The pivot point F_1 is located on the frame on a line through the point G_1 parallel with the line C_1 I_3 and at a distance from G_1 equal to the distance between the points C_1 and I_3 . It will be apparent that the triangle formed by the pivot points G_1 F_1 E_1 is identical in angles and dimensions with the triangle formed by the fundamental points C_1 I_3 D ; and that the third side F_1 20 E_1 of one will be parallel with the third side I_3 D of the other, for all positions of adjustment.

The pivot points on the PT end frame are located at the same relative distance and position as on the PC end, but in the reverse direction. 25 Because of the fact that with the instrument adjusted to an arc of a circle the points I_3 D and I_4 are held in a straight line, the line through the pivot points F_1 E_1 at the PC end will be in the same straight line with the line through the pivot 30 points F_2 E_2 at the PT end—the straight center line of the bar K illustrated in Figs. 1 and 2.

In the construction of this instrument I do not limit myself to the choice of the fundamental points shown in Fig. 4, which govern the location of the pivot points. I may use another set of fundamental points, for example, like those used in the construction of the instrument illustrated in Patent 1,893,689, and specifically pointed out in the geometric diagram of Fig. 7 40 in that patent.

I claim as my invention:

1. An adjustable curve ruler for drawing arcs of circles comprising a flexible arc member of constant length, end members rigidly attached to the ends of the arc member, a set of six bars pivotally connected together and to the end members, each end member together with three of said bars forming through the pivotal connections a parallelogram, and means in combination with said parallelograms for controlling the relative angular movements at said pivotal connections whereby the said end members are held at the correct angle and the correct distance apart with the flexible arc member curved to an arc of a circle. 55

2. An adjustable curve ruler for drawing arcs of circles comprising a flexible arc member of constant length, end members rigidly attached to the ends of the arc member, a base element, said end members being pivoted to said base element, parallel link pairs respectively connected to said end members and connected to each other for unitary pivotal movement relative to each other about a common pivot axis, the pivotal connection between one of said end members and the base element being adjustable toward and from the pivotal connection between the other end member and the base element, and means for locking the ruler in adjusted position. 65
